[57] CLAIM

The ornamental design for a combined faucet pix and adaptor therefor, as shown and described.

DESCRIPTION

FIG. 1 is a front perspective of a combined faucet pix and adaptor therefor showing my new design;

FIG. 2 is a front perspective view of a second embodiment of FIG. 1, it being understood that the only difference from the first embodiment resides in the wand tip;

FIG. 3 is a top plan view of the first embodiment;

FIG. 4 is a front elevational view thereof;

FIG. 5 is a bottom plan view thereof; and,

FIG. 6 is a side elevational view thereof, looking from the left side of FIG. 4, the opposite side being a mirror image thereof.

It is understood that the tubing projecting from the wands and adaptor is of indeterminate length.
